CLAIM

The ornamental design for a detergent bottle cap, as shown and described.

DESCRIPTION

FIG. 1 is a top right perspective view of a detergent bottle cap showing the new design;

FIG. 2 is a front side plain view thereof;

FIG. 3 is a top plain view thereof;

FIG. 4 is a cross sectional view of the detergent bottle cap, taken along lines 4-4 of FIG. 3;

FIG. 5 is a bottom left perspective view thereof; and,

FIG. 6 is a bottom plain view our detergent bottle cap design.

In FIG. 3, the broken lines depicted represent a sectional designation that forms no part of the claim.
